FLASHING SIGNAL UNIT

Robert D. Kahn, 24 Maple Ave.,
Rockville Centre, N.Y. 11570

Continuation-in-part of design application Ser. No. 9,385,
Nov. 13, 1967. This application May 23, 1968, Ser. No.
12,591

Term of patent 14 years

Int. Cl. D29—99

U.S. Cl. D72—1

FIG. 1

FIG. 5

FIG. 6

FIG. 2

FIG. 3

FIG. 4

FIG. 1 is a perspective view of the flashing signal unit showing my new design;

FIG. 2 is a right side elevational view thereof, the left side elevational view thereof being identical;

FIG. 3 is a front elevational view thereof, the rear elevational view being identical;

FIG. 4 is a bottom plan view thereof;

FIG. 5 is a perspective view of a second embodiment of the flashing signal unit; and

FIG. 6 is a perspective view of a third embodiment of the flashing signal unit.

This is a continuation-in-part of design application Ser. No. D. 9,385, filed Nov. 13, 1967, now design Pat. No. D. 212,722.

I claim:

The ornamental design for a flashing signal unit, as shown and described.
